UNITED STATES PATENT OFFICE.

AUGUST BECK, OF NEW YORK, N. Y.

QUILTING-MACHINE.

SPECIFICATION forming part of Letters Patent No. 276,657, dated May 1, 1883.

Application filed January 26, 1883. (No model.)

To all whom it may concern:

Be it known that I, AUGUST BECK, of the city, county, and State of New York, have invented certain new and useful Improvements in Quilting-Machines, of which the following is a specification.

This invention has reference to an improved quilting-machine in which the quilting is accomplished by a single gang of needles that is placed either at a suitable angle of inclination or parallel to the direction of motion of the fabric to be quilted.

The invention consists in the combination of a vertically-reciprocating needle-bar having a single gang of needles, a longitudinally-guided feed-carriage, a feeding mechanism, and a carriage-reciprocating mechanism of special construction, arranged in connection with said feeding mechanism, as hereinafter described and claimed.

In the accompanying drawings, Figure 1 represents a side elevation of my improved quilting-machine. Fig. 2 is a plan; Fig. 3, a rear elevation. Figs. 4 and 5 are respectively a side elevation, partly in section, on line *xx*, Fig. 5, and a vertical transverse section of the mechanism by which reciprocating motion is imparted to the feed-carriage. Fig. 6 represents a detail vertical transverse section and a longitudinal section of the shaft and pinion by which motion is imparted to the feed-rollers. Fig. 7 is a plan of a modified construction of the quilting-machine, with the needle-bar arranged parallel to the direction of motion of the fabric. Fig. 8 is a detail side view of the grooved plate by which reciprocating motion is imparted to the feed-carriage, and Fig. 9 is a horizontal section of said plate on line *yy* of Fig. 8.

Similar letters of reference indicate corresponding parts.

Referring to the drawings, A represents the supporting-frame of my improved quilting-machine. The frame is made of oblong shape, and provided at one end with upright and forward-bent standards A', which serve to guide the vertically-guided needle-bar B, having a single gang of needles. The needle-bar B is reciprocated by any approved mechanism. The needle-bar B is supported by the standards A' at an angle of forty-five degrees across

the fabric to be quilted, in which case one of the supporting-standards A' is lengthened and the other shortened, so as to provide for this position of the needle-bar, as shown in Figs. 1 and 2.

The frame A is provided at its longer sides with longitudinal guide-rods *a*, which are supported in fixed brackets *a'*. To these guide-rods *a* the feed-carriage C is applied at both ends by upright standards C', which carry in suitable bearings the feed-rollers C² C³.

The fabric to be quilted is wound upon a roller, *b*, supported in suitable bearings at one end of the feed-carriage C, and retained by a suitable tension device. It is then conducted over a guide-roller, *b'*, to the first pair of feed-rollers, C², and then transversely across the feed-carriage C to the second pair of feed-rollers, C³, at the opposite end of the feed-carriage. The second pair of feed-rollers, C³, receives intermittent rotary motion from a fixed worm-segment, *d*, on the flanged wheel D at the end of the driving-shaft D', said worm-segment engaging at each revolution of the driving-shaft a pinion, D², the teeth of which are placed at an angle of inclination to the axis of the pinion-shaft. A flange, *d'*, extends around that part of the circumference of the wheel D which is not taken up by the worm-segment *d*, so as to engage the pinion D² and stop the same until the worm-segment *d* engages into the teeth of the pinion and moves the same around its axis. The shaft of the pinion D² turns in bearings of the frame A, and is provided at the rear end with a gear-wheel, *e*, which meshes with the gear *e'* on a longer shaft, *e'*, arranged below the shaft of the pinion D², and parallel thereto, the shaft *e'* turning in bearings of frame A, and of one of the upright standards C' of the feed-rollers C³, as shown in Fig. 1.

On the shaft *e'* is arranged a gear-wheel, *e*³, which meshes with a gear-wheel, *e*⁴, attached to the shaft of the lower feed-roller, C². The gear-wheel *e*³ is adapted to slide longitudinally on the shaft *e'*, together with the carriage C, the shaft being provided for this purpose with a longitudinal groove, *f*, and the hub of the gear-wheel with a fixed spline, *f'*, which moves in the groove *f*, as shown in detail in Fig. 6. The gear-wheel *e*³ is provided with a grooved

collar, e^5 , which is secured to a corresponding annular recess of the upright standard C' of the feed-rollers C^3 by means of transverse keys f^2 . By means of this connection the pinion is 5 compelled to traverse, with the supporting-standards C' of the feed-rollers C^3 , along the shaft e^2 without being prevented from rotating with the same, so as to transmit thereby intermittent rotary motion to the gear-wheels 10 at the ends of the feed-roller shafts and an intermittent forward feed to the fabric.

The feed-carriage C receives also intermittently reciprocating motion simultaneously with the revolving motion imparted to the feed-rollers in a direction at right angles to the direction of the feed of the fabric. This reciprocating motion is imparted by means of a special mechanism which forms the essential feature of my invention. This mechanism is 15 shown in detail in Figs. 4 and 5, and consists of a short shaft, g , that turns in bearings of one of the standards A' of the needle-bar, and of a bracket-plate, g^2 , that is attached to a stationary upright plate, g' , at the rear part of the 20 supporting-frame A .

Intermittent rotary motion is imparted to the shaft g by intermediate mechanism from the shaft e^2 , said intermediate mechanism consisting of a shaft, h , that turns in bracket-bearings of frame A parallel to shaft D' . Shaft e^2 meshes, by a bevel-gearing, $h' h'$, with shaft h , and the latter, by a gear-wheel, h^2 , with the gear-wheel g^3 on the shaft g , as shown clearly in Fig. 2. The shaft g is made of two parts, 35 which are connected by a universal joint, g^4 . The outermost end of the jointed shaft g is guided in parallel grooves g^5 , having semicircular connecting portions, of a slide-plate, g^6 , which latter is guided in parallel horizontal 40 flanges g^7 of the upright plate g' . The horizontally-guided plate g^6 is arranged with a central row of horizontal projecting pins g^8 , which are engaged by the teeth of a pinion, g^9 , near the end of shaft g . The pins g^8 are arranged 45 for this purpose at such a distance from each other as to admit the proper meshing of the pinion therewith. The semicircular end portions of the grooves g^5 serve to guide the shaft from the upper to the lower groove, and vice 50 versa, in following the pinion g^9 around the pins g^8 . The shaft g is guided near the pinion g^9 along the inclined slot g^{10} of a fixed plate, g^{11} , said inclined slot serving to facilitate the turning of the pinion g^9 around the 55 end pins from the upper into the lower groove.

The intermittent rotary motion of the shaft g imparts, by the pinion g^9 and pins g^8 , intermittent reciprocating motion to the slide-plate g^6 , which is pivoted by an extension-arm, g^{12} , 60 to the feed-carriage C . The latter receives thereby intermittent reciprocating motion, that takes place simultaneously with the lateral motion which is imparted to the fabric to be quilted by the feed-rollers and their transmitting mechanism. When both the fabric and feed-carriage are at a point of rest the needles

descend and make a stitch, which is repeated, so as to produce zigzag lines of stitches over the entire fabric, which lines touch at the corners, and give thereby the appearance of continuous diagonally-intersecting lines of stitches, 70 as shown in Fig. 2.

When it is desired to quilt the fabric in larger or smaller squares of stitches the guide-plate g^6 is lengthened or shortened by inserting between or removing from the two end sections of the same, which are connected by overlapping shoulders and clamp-screws, intermediate pieces, g^{13} , having additional center pins, as shown in dotted lines in Figs. 4, 80 and 9.

If twice the size of the regular squares is desired to be made to that which is usually made on the machine, one or more intermediate needles are removed and a corresponding length 85 of section inserted into the slide-plate g^6 , so as to produce thereby the required degree of reciprocating motion for the feed-carriage. For this purpose the grooves of the slide-plate have to be equal in length to one-half of the 90 diagonal of the squares formed by the zigzag lines of stitches.

In place of arranging the needle-bar at an angle of forty-five degrees, it may be arranged at any other oblique angle, and also, if desired, parallel to the direction of the feed, as shown in Fig. 7, in which case the supporting-standards of the needle-bar are of equal length. In this case, however, the quilting is not accomplished by longitudinal zigzag lines 100 that touch each other at their corners, but by diagonally-intersecting lines of stitches. Consequently the guide-plate g^6 has to be equal in length to the width of the fabric to be quilted. The lines of stitches cross each other at right 105 angles by the reversing of the motion of the feed-carriage, as indicated in dotted lines in Fig. 7.

The remaining accessories—such as shuttle-carriers, shuttle-motion, thread-tensions, &c.— 110 are not shown in the drawings, as they are of the same construction as those usually employed in quilting-machines heretofore in use.

By my improved construction a single gang of needles produces the uniform quilting of 115 the fabric, either in longitudinal zigzag lines which touch each other at the corners or by diagonally-intersecting lines of stitches, as shown respectively in Figs. 2 and 7, and by means of a mechanism which produces a regular 120 intermittent reciprocating motion of the feed-carriage simultaneously with the intermittent lateral motion of the fabric.

Having thus described my invention, I claim as new and desire to secure by Letters Patent— 125

1. The combination of a frame having guideways, a carriage movable in said guideways, a gang of vertically-reciprocating needles, a cloth-feeding mechanism, and mechanism for imparting a reciprocatory motion to said carriage, consisting of the shaft h , provided with the gears $h' h^2$, the shaft g , provided with pin-

ions g^3 g^4 and universal joint g^4 , the frame g' , having guideways, and the slide-plate g^6 , having a central row of pins, g^8 , a surrounding groove, g^5 , and an extension-arm, g^{12} , substantially as described.

2. The stationary plate g' , having guideways, the slide-plate g^6 , movable in said guideways, provided with a row of pins and a surrounding groove, a bracket attached to said stationary plate, having a shaft-bearing at its outer end, a shaft which rests in said bearing, provided with a universal joint and pinions, one end of said shaft projecting into the groove of

said slide-plate, while a pinion near said end meshes with the pins on said plate, a slotted guide-plate, g^{11} , and a boss on the swiveling part of said shaft, in combination with the carriage and the feeding and sewing mechanisms, substantially as described.

In testimony that I claim the foregoing as my invention I have signed my name in presence of two subscribing witnesses.

AUGUST BECK.
